CLAIM

The ornamental design for a pair of sofa arm rest forms, as
shown and described.

DESCRIPTION

FIG. 1 is a front perspective view of a pair of sofa arm rest forms.

FIG. 2 is another front perspective view of the pair of sofa arm rest forms of FIG. 1.

FIG. 3 is another front perspective view of the pair of sofa arm rest forms of FIG. 1.

FIG. 4 is a rear perspective view of the pair of sofa arm rest forms of FIG. 1.

FIG. 5 is another rear perspective view of the pair of sofa arm rest forms of FIG. 1.

FIG. 6 is a front elevational view of the pair of sofa arm rest forms of FIG. 1.

FIG. 7 is a rear elevational view of the pair of sofa arm rest forms of FIG. 1; and,

FIG. 8 is a top plan view of the pair of sofa arm rest forms of FIG. 1.

The broken lines in the figures are for the purpose of
illustrating portions of the pair of sofa arm rest forms, which
form no part of the claimed design.

1 Claim, 8 Drawing Sheets

Related U.S. Application Data

a continuation of application No. 29/738,180, filed on Jun. 15, 2020, now Pat. No. Des. 957,173.
